Primary Examiner — Jennifer Rivard*Assistant Examiner* — Alison M Ofstun(74) *Attorney, Agent, or Firm* — Harold H. Bennett, II(57) **CLAIM**

The ornamental design for a carabiner multi-tool, as shown and described.

DESCRIPTION

FIG. 1 is a front perspective view of a carabiner multi-tool; showing my new design.

FIG. 2 is a top plan view thereof.

FIG. 3 is a right side elevational view thereof.

FIG. 4 is a front elevational view thereof.

FIG. 5 is a left side elevational view thereof.

FIG. 6 is a rear elevational view thereof; and,

FIG. 7 is a bottom plan view thereof.

Features represented in broken lines form no part of the claimed design.

1 Claim, 4 Drawing Sheets(56)
